UNITED STATES PATENT OFFICE.

ANTON KUSEBAUCH, OF PITTSBURG, PENNSYLVANIA, ASSIGNOR, BY MESNE ASSIGNMENTS, TO NEBNST LAMP COMPANY, A CORPORATION OF PENNSYLVANIA.

COOLING-VANE FOR SECOND-CLASS GLOWER-LAMPS.

977,198.

Specification of Letters Patent. Patented Nov. 29, 1910.

Application filed November 11, 1908. Serial No. 482,122.

To all whom it may concern:

Be it known that I, ANTON KUSEBAUCH, a citizen of the United States, residing in Pittsburgh, in the county of Allegheny and State of Pennsylvania, have made a new and useful Invention in Cooling-Vanes for Second-Class Glower-Lamps, of which the following is a specification.

This invention relates to incandescent lamps in which the filaments are composed of second-class conductors.

One object of this invention is to produce a lamp of the class described of improved and compact design which will more perfectly fulfil the purpose for which it is intended than those now generally in use.

Other objects and advantages of this invention will be specifically described hereinafter, it being understood that changes in form, proportion and minor details of construction may be resorted to without departing from the spirit of the invention.

In the drawings accompanying this application and forming a part thereof: Figure 1 is a sectional elevation of a lamp embodying my invention; Fig. 2 is a section along the line A A of Fig. 1 and illustrates a cooling device which forms a detail of my invention; Fig. 3 is a perspective view of a cooling vane employed in my invention; and Fig. 4 is an elevation of a modification of my invention.

In the lamp illustrated, I have embodied improvements which constitute my invention and which I believe perfect the operation of the lamp.

The cooling and ventilating system employed is an improvement and its use eliminates certain serious difficulties which have been previously encountered. In previous lamps a heavy overshoot of current passed through the glower directly after the glower was thrown into action by the automatic cutting out of the heater. This overshoot current sometimes reached a point far beyond the normal operating capacity of the lamp and resulted from the fact that the ballast contained heat absorbing material and furthermore that the heat radiated by the ballast was not sufficiently taken care of. These conditions reacted on the ballast characteristic in such a manner as to cause it to gradually perform its function, that is, to take less and less current until the normal

temperatures of the lamp were eventually reached. A current of 150 or 160 per cent. of the normal operating current of the lamp was forced through the glowers immediately after they were started. With this excess current flowing through the glower, even for a very limited period, it is evident that it was strained considerably, in fact was strained a greater amount than if they had been operated at a higher efficiency with the starting overshoot removed. The air cooling device as illustrated in the drawings overcomes these objectionable features and reduces the overshoot, (the abnormal current flowing through the glowers at the period of starting) to practically zero. I have accomplished this by increasing the radiating surface of the ballast and so constructing a ventilating system that the energy dissipated in the ballast wire and carried off in the form of heat is quickly radiated and convected to the surrounding air.

Referring to the drawings: The lamp includes a porcelain 5 on which a terminal plug 6 of the lamp is mounted, a bottom or socket porcelain 7, in which a screw base 8 is secured, a ballast tube 9 which is located between the top and bottom porcelains, and a cut out device 10 which is mounted on the top porcelain. These elements together with a number of separately formed bronze cooling vanes 11 are inclosed within a shell or casing 12. The mounting terminal 6 is secured to the porcelain 5 and consists of a cylindrical shell 13 provided with threads to fit a mounting socket and a circular terminal 14 which is surrounded by the cylindrical shell and is insulated therefrom.

A glower 15 and a heater 16 are mounted on the screw base 8. This base is provided with a screw plug 17, which is adapted to be screwed into a socket provided on the porcelain 7. Three separate terminals are provided on the screw base, one for the glower, one for the heater, and one common to the glower and the heater. Each of these terminals contact with a correspondingly located terminal provided in the socket of the porcelain 7 and connect the glower and the heater into their respective circuits. The ballast tube 9 incloses a ballast wire 18 and is filled with an inert gas. A base portion 19 is provided for the ballast tube which forms a mounting plug for the tube

and terminals for the wire. A socket 21 is secured to the porcelain 6 and is adapted to receive the base portion 19 and to electrically connect it into the glower circuit of the 5 lamp.

The terminals 13 and 14 are terminals of the lamp circuit and the lamp circuit includes a heater circuit and a glower circuit connected in parallel. The glower, the ballast 10 wire and the magnetic coil of the cut-out device are located in the glower circuit, and the heater and the armature of the cut-out device are located in the heater circuit. After the glower has reached a temperature 15 at which it is a current conductor, the magnetic coil of the cut-out device is energized and, by attracting the armature, breaks the heater circuit and causes all of the current to flow through the glower circuit. 20

The cut-out device consists of a magnetic coil 22 which is included in the glower circuit and which controls a swinging armature 23 mounted on the support frame of the coil. The armature is included in the 25 heater circuit when the coil 22 is not energized. The cooling device consists of a number of separately formed phosphorous bronze pieces or vanes 11 which surround the ballast tube 9 and are located between it and the shell portion 12 of the lamp. These pieces are so shaped that they mutually hold each other in place and by their own resilience firmly clutch the ballast tube, 30 so that the heat is transmitted from the glass walls to the pieces by contact. The vanes, besides presenting a large radiating surface, form passages and with openings 35 in the shell 12 aid in the production of 24 in the shell 12 aid in the production of 40 convection currents which are effective in carrying off the heat generated in the ballast.

The shell 12 is so formed that the porcelain 45 6 may be readily removed so that the ballast bulb may be replaced or that other repairs may be made to the lamp. A cover portion 26 through which the mounting and terminal plug 6 projects is provided for the shell 12 and secures the porcelain 6 in place.

50 In differently constructed lamp bodies I have found it convenient to employ the same shape of cooling vanes 11. I inclose these, however, in a cylindrical shell which when in place is concentric with the ballast 55 tube and is supported on the tube by means of coöoperating vanes 11. This construction is illustrated in Fig. 4. The ballast tube is secured in place in a socket 21 and the cylinder 28, in which the vanes 11 are mounted, 60 is slid to place on and around the ballast bulb. The vanes 11 are arranged in this

cylinder precisely as they are shown in Fig. 2.

In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.

What I claim is:

1. In combination with a ballast tube, of a lamp the filaments of which are composed of second-class conductors, a cylindrical shell located concentrically with said tube and resilient vanes located within said shell and held by their resilience in contact with said tube. 75

2. In combination with the inclosing shell of a lamp in which the filaments are composed of second-class conductors, a ballast tube located concentric within said shell and resilient vanes located within said shell and held by their resilience in contact with said tube. 85

3. In combination with the inclosing shell of a lamp in which the filaments are composed of second class conductors, a ballast tube located concentrically within said shell and a plurality of resilient vanes located within said shell surrounding said tube and held in contact therewith. 90

4. In combination with the inclosing shell of a lamp in which the filaments are composed of second-class conductors, a ballast tube located concentrically within said shell and a plurality of radially extending cooling vanes located between said shell and said ballast tube. 95

5. In combination with the inclosing shell of the body portion of a lamp, a ballast tube, a plurality of separately formed resilient cooling vanes surrounding said tube and located between it and said shell. 105

6. In combination with the inclosing shell and the body portion of a lamp, a ballast tube, a plurality of separately formed radially extending cooling vanes surrounding said tube and located between it and said shell and ventilating apertures provided in said shell above and below said vanes whereby convection currents are caused to circulate between and over said vanes. 110

In testimony whereof, I have hereunto subscribed my name this seventh day of November, 1908.

ANTON KUSEBAUCH.
